Inventor:
Joh. Brödl
UNITED STATES PATENT OFFICE

JAKOB BRÖDL, OF MUNICH, GERMANY

INSOLE

Application filed April 4, 1931, Serial No. 527,741, and in Germany February 26, 1931.

This invention relates to an insole, chiefly for feet, which are not orthopedically perfectly formed, and presents the advantage that therein neither metal nor rivets, which show through, when the insole is being worn, nor rubber, which makes the foot unnecessarily hot, is employed.

According to the invention the insole consists of a leather sole cut to the desired shape and pressed to the required curvature, on which a piece of plaited gut strings is inserted so that a hollow space is formed between this piece and the sole. This hollow space is reduced when the insole is loaded by the foot and again enlarges when the insole is relieved.

Such an insole can according to the way in which it is made be employed for all kinds of deformed feet, for example flat feet, hollow insteps, weak insteps, splay feet and the like. As compared with the known insoles it possesses the advantage that the hollow of the foot does not rest on a rigid support, but that this support is resilient so that the foot can easily carry out a rolling movement in forward direction.

An embodiment of the invention is illustrated by way of example in the accompanying drawing in which:—

Fig. 1 shows a right hand insole in bottom plan view.

Fig. 2 is a longitudinal section of Fig. 1.

Fig. 3 is a perspective view of Fig. 1.

Fig. 4 shows how such an insole must be made for example for splay feet.

Fig. 5 shows an insole made for a hollow instep.

a designates the suitably pressed and cut leather piece, *b* designates the longitudinal staying by means of gut strings, *c* the transverse staying and *d* the known lateral support of the insole.

The section Fig. 4 taken on line *x*—*x* of Fig. 3 shows how such an insole must be made for splay feet so that a pad or raised portion *h*, which bears under the small ball, can be applied, whereas a further padding or raised portion *g* is assumed for the lateral correction of the foot.

In Fig. 5 *i* designates the depression for

the heel and *k* the depression for the large toe ball in insoles for hollow insteps.

The under side of the gut stringing may evidently also be covered with a cover *f*, and the insole may have a cover *e* on the bottom and on the top. Consequently, as may be seen, the insole can be constructed for any deformed foot, the stringing being increased at points, which are heavily loaded and reduced at points, which are less heavily loaded. Such an insole is comfortable and prevents foot diseases also in the case of healthy feet.

I claim:—

1. An insole for feet to be orthopedically treated, comprising in combination a piece of leather cut to size and curved like an insole, and an element composed of longitudinal and transverse gut strings stretched on the concave side of said piece of leather, connected at their ends directly to said piece of leather and interconnected at their points of intersection and adapted to limit the depressing of the curved portion of the insole and to return said piece of leather into its initial curved shape when the insole is not loaded.

2. An insole as specified in claim 1, in which both the longitudinal and the transverse gut string stayings are closer spaced at points subject to heavy load than at points less heavily loaded.

3. An insole as specified in claim 1, in which the piece of leather has depressions and raised portions for the deformed points and for correcting same.

In testimony whereof I affix my signature.

JAKOB BRÖDL.
